UNITED STATES PATENT OFFICE.

JESSE B. THOMAS, OF BOSTON, MASSACHUSETTS, ASSIGNOR OF ONE-HALF TO
ALFRED J. KNIGHT, OF BROOKLINE, MASSACHUSETTS.

CHEMICAL FIRE-EXTINGUISHER.

No. 857,544.

Specification of Letters Patent.

Patented June 18, 1907.

Application filed January 8, 1906. Serial No. 295,003.

To all whom it may concern:

Be it known that I, JESSE B. THOMAS, a citizen of the United States, and a resident of Boston, county of Suffolk, State of Massachusetts, have invented an Improvement in Chemical Fire-Extinguishers, of which the following description, in connection with the accompanying drawings, is a specification, like letters on the drawings representing like parts.

This invention relates to chemical fire extinguishers of the type wherein an acid receptacle or bottle is contained within a canister provided with a suitable alkaline solution, the acid-bottle being provided with a stopper which opens the bottle mouth when the extinguisher is inverted for use, to effect the requisite commingling of the acid and alkaline contents.

My invention has for its objects the production of certain novel features of construction whereby the closure and sealing of the canister is effected in a better and more effective manner than is now attained while eliminating certain objectionable features, and my invention also comprehends simple and efficient means for suspending the acid-bottle and for guiding the stopper thereof when the extinguisher is used.

Canisters have heretofore been provided with a threaded neck to engage a cover which is screwed down upon a packing ring or gasket, to tightly seal the canister, but at times the screwing on of the cover displaces or injures the packing, decreasing the sealing efficiency, and so too, when a cover has been undisturbed for some time the deterioration of the packing, or corrosion, will cause the cover to bind so tightly that frequently it is bent or broken, or other parts of the extinguisher injured, in the effort to remove the cover. In my present invention the sealing pressure exerted upon the packing is a direct force acting at right angles to it, with no rotative or twisting action the closing means for the canister comprising a cover which closes the opening of the canister, and a separable cap which is adapted to be screwed upon the canister neck and by direct engagement with the exterior face of the cover makes a sealing engagement with the packing.

The various novel features of my invention will be fully described in the subjoined specification and particularly pointed out in the following claims.

Figure 1 is a vertical diametral section of the upper portion of a chemical fire extinguisher embodying one form of my invention, a portion of the acid-bottle and its gravity stopper being shown in elevation; Fig. 2 is a similar view showing a different form of bottle-holder and manner of suspending the same, with a combined bottle-stop and guide for the stopper when the extinguisher is inverted; Fig. 3 is a like view, showing a bottle-holder similar to that shown in Fig. 2, but with different means for retaining the acid-bottle in place, and illustrating the stopper-guide at the center of the cover; Fig. 4 is a diametral section of the screw cover shown in Figs. 1, 2 and 3, and Fig. 5 is a modified form of closure for the canister, to be referred to.

The sheet-metal canister 1, of well known shape and construction (only the upper portion being herein shown) has a nipple 2 for the usual hose 3, and the open upper end of the canister is soldered or otherwise tightly secured to an upright neck 4, Figs. 1, 2 and 3, said neck having an external screw-thread 5. An internal flange or shoulder 6 on the neck is provided on its upper face with an annular seat 7, to receive a packing ring or gasket 8 of rubber or other suitable packing material, the outer side wall of the seat being shown as undercut at 9 to hold the packing ring in the seat, the inner wall of the latter being shown at 10.

A circular, imperforate metal cover 11, preferably concavo-convex as shown, is provided with an annular depending portion or lip 12 on its under face adjacent its periphery, to rest upon the packing ring, the diameter of the cover being such that it will slip readily into the part of the neck 4 projecting above the packing. At its center the cover is shaped to present a hollow projection 13, for a purpose to be described, the lip 12 being of such thickness that it will engage only the packing ring, and no portion of the seat thereof.

An internally screw-threaded, annular cap 14 is adapted to engage the thread 5 of the canister neck, and to be screwed down thereon, a circular rim 15 secured to the cap by arms 16 affording a firm grasp in opening and closing the extinguisher and also in using the same. The open center of the cap permits the projection 13 of the cover to extend through it, and by reference to Figs. 1, 2 and

3 it will be seen that the cap directly engages the exterior face of the cover, but at or near its periphery, substantially directly above the lip 12.

- 5 When the cover 11 is in place the cap is applied to the neck and screwed down, forcing down the cover and pressing the lip 12 into perfect sealing engagement with the packing ring 8 throughout its extent, hermetically closing the canister. There is no rotative movement whatever to the cover, but only a powerful, straight downward pressure directly applied, so that there is no rubbing or abrading action between the contacting surfaces of the opposed annular lip and the packing ring.

In order to reduce the friction between the cap and cover when screwing down the former I prefer to provide the cap with a series of 20 separated engaging portions or lugs 17, most clearly shown in Fig. 4, which bear upon the cover.

The construction so far described is the same in Figs. 1 to 3 inclusive, and it will be 25 seen that even should the packing ring deteriorate or corrode sufficiently to stick to the cover the cap can be easily unscrewed and thereafter the cover can be readily released.

30 By the construction described a hermetic seal can be secured with a much smaller expenditure of force in screwing down the cap, as there is no "drag" or resistance to be overcome between the packing and the cover 35 engaging the same.

Referring to Fig. 1, the acid-bottle 18 is supported in a cage-like holder 19, having a threaded hub 20 which screws onto a depending tubular and externally - threaded 40 boss 21 on the cover 11, so that the acid-bottle is suspended from the cover in the canister. A cross-brace 22 on the holder prevents displacement of the bottle when the extinguisher is inverted, and a gravity stopper 23 closes the bottle mouth when the extinguisher is in normal, upright position, said stopper having an outer tapered projection 24. When the extinguisher is inverted the 45 said projection enters the boss 21 and the hollow projection 13 of the cover, and is guided thereby, being held in position to resume its closing position on the bottle when the extinguisher is again turned upright.

In Fig. 2 the bottle-holder 25 is made of 55 sheet metal, having an open bottom of less diameter than the bottle, and with holes 26 to permit the contents of the bottle and canister to commingle when the extinguisher is used. At its upper end the bottle-holder has 60 a lateral annular flange 27 which rests upon the top of the inner side wall 10 of the packing seat 7, so that the holder is suspended in a detachable manner from the neck of the canister.

65 A tubular bottle-stop 28 is secured to and

depends from the cover 11, to abut against the breast of the acid-bottle 18 when the extinguisher is inserted, said stop loosely surrounding the gravity stopper 23 and assisting the hollow projection 13 in guiding the same, 70 said tubular stop being perforated at 29.

The bottle-holder slides snugly into place within the annular flange 6 of the neck, and can only move against the cover 11 when the canister is turned upside down.

In Fig. 3 the bottle-stop just referred to is omitted, and instead the tubular bottle-holder 25 has externally secured to it spring wires 29 upturned against its sides and bent at 30 to project through adjacent ones of the 80 holes 26 above the breast of the bottle 18, the wires springing outward when the bottle is pushed into the holder or drawn out therefrom. The upper, free ends of the wires extend between the bottle-holder and the flange 85 6 on the canister neck 4, and the flange 31 is made a little wider than the flange 27, Fig. 2, to bridge the space and rest on the wall 10 as before.

In Fig. 3 the hollow projection 13 of the 90 cover 11 serves as the sole guide for the stopper 23, receiving the projection 24 thereof when the stopper drops away from the bottle mouth as the extinguisher is reversed, and directing the stopper back and preventing 95 its displacement when it again seats on the bottle.

While I have thus far shown the packing ring as held in a seat on the interior of the neck of the canister, with the opposed sealing 100 lip on the removable cover, the reverse arrangement of lip and packing ring is manifestly within the scope of my invention, and is illustrated in Fig. 5. Referring to said Fig. 5 the neck 32 of the canister 1 is externally threaded, as before, for the cap 14, the construction of the latter being the same as has been already described, but the neck has an upturned annular lip 33 to co-operate 105 with the packing ring or gasket 34 held in an annular seat 35 formed in the under face of the cover 36. The inner side wall of the seat is shown as undercut at 37 to hold the packing ring in place, the lip 33 and packing ring being opposed and forced into sealing 110 engagement by screwing down the cap 14, the latter bearing directly on the exterior face of the cover 36, as before. Said cover is provided with the central hollow projection 38, for the purpose previously set forth, 115 and as the bottle-holder cannot in this arrangement be conveniently suspended from the neck of the canister I prefer to use the suspending means and such a bottle-holder as shown in Fig. 1. For this purpose, the 120 cover 36 is provided with the depending and externally threaded boss, 39, Fig. 5. It will be seen that not only does the hollow projection on the cover serve as a guide for the stopper, but it also serves as a handle or 125 130

hand-piece by means of which the cover can be easily lifted into place, or removed from the canister after the retaining cap has been unscrewed.

5. Whichever embodiment of my invention is concerned it will be manifest that the sealing of the canister is effected by the coöperation of an annular lip and an opposed annular packing, the sealing being effected by a direct downward pressure upon the said two parts, without any rotative or abrading movement of the one relative to the other.

Having fully described my invention, what I claim as new and desire to secure by Letters Patent is:—

15. In a chemical fire-extinguisher, a canister having an externally-threaded neck, a cover having an outwardly extended stopper guide formed thereon, an annular lip on one and an opposed annular seat on the other of said members, a packing ring in the seat, to be engaged by the lip, an acid receptacle suspended within the canister, a gravity stopper therefor, and a cap having an open center to permit the stopper-guide to pass through it and adapted to screw onto the neck and directly engaging the exterior face of the cover, to force the lip into sealing engagement with the packing ring as the cap is 30 screwed down.

20. In a chemical fire-extinguisher, a canister having an externally threaded neck, a cover having a central hollow projection integral therewith and forming a stopper guide, an annular lip on one and an opposed annular seat on the other of said members, a packing ring in the seat, to be engaged by the lip, an acid receptacle suspended within the canister, a gravity stopper therefor, and a 25 cap having an open center and adapted to screw onto the neck and directly engaging the exterior face of the cover, to force the lip into sealing engagement with the packing ring as the cap is 35 screwed down.

projection on the cover extending through 45 the opening in the cap.

3. In a chemical fire extinguisher, a canister having an upright, externally threaded neck provided with an internal horizontal flange below its top, an annular seat in 50 the upper face of the flange, the outer side wall of the seat being undercut, a packing ring in the seat held in place by the undercut wall, an acid-bottle holder detachably suspended from the inner wall of the seat, inside 55 the packing ring and out of engagement therewith, a cover having a depending annular lip to bear upon the exposed face of said packing ring between the inner and outer walls of the seat, and a cap to screw upon 60 the neck and directly engaging the exterior face of the cover to force the lip thereof into sealing engagement with the packing ring.

4. In a chemical fire-extinguisher, a canister having an externally threaded neck, a 65 cover having a central hollow projection, outwardly extended therefrom, an annular lip on one and an opposed annular seat on the other of said members, a packing ring in the seat, to be engaged by said lip, an acid-bottle, a holder therefor detachably suspended within the canister, a gravity stopper for the bottle and guided by the hollow projection on the cover when the extinguisher is inverted, and an annular cap adapted to 70 screw onto the neck and having a series of separated lugs integral therewith to directly engage the exterior of the cover, to force the lip and packing ring into sealing engagement, the hollow projection on the cover extending through the open center of the cap. 75

In testimony whereof, I have signed my name to this specification, in the presence of two subscribing witnesses.

JESSE B. THOMAS.
